UNITED STATES PATENT OFFICE.

CHARLES F. STOCK, OF PEORIA, ILLINOIS; N. GRIER MOORE, ADMINISTRATOR OF SAID CHARLES F. STOCK, DECEASED, ASSIGNOR, BY MESNE ASSIGNMENTS, TO THE PEORIA TARGET COMPANY, OF SAME PLACE.

TRAP FOR THROWING TARGETS.

SPECIFICATION forming part of Letters Patent No. 322,020, dated July 14, 1885.

Application filed October 13, 1884. (No model.)

To all whom it may concern:

Be it known that I, CHARLES F. STOCK, a citizen of the United States, residing in Peoria, in the county of Peoria and State of Illinois, 5 have invented certain new and useful Improvements in Traps for Throwing Flying Targets, of which the following is a specification.

My invention pertains to that class of traps 10 which are designed to send or throw through the air targets made of light fragile material, usually called "clay pigeons," said traps having a throwing or sending arm which holds the target upon one end, and which is operated 15 from the other end. In the traps heretofore patented and now in use the target has been removably secured to the sending or throwing arm by means of a tongue or cord secured to the target engaging a spring device on the 20 end of the arm. When this arm is swung round to throw the target, centrifugal force will give to it an uncertain amount of axial rotation; but, as found by practical experience, this impulse is not sufficient to overcome the 25 force of the wind which may be blowing at the time, nor have the targets sufficient axial rotation to cause an even and steady flight; consequently they "wabble" more or less, and cannot be thrown to any considerable 30 distance, nor is the distance to which they can be thrown at all positive.

My improvement consists in providing the 35 end of the sending or throwing arm with a pivotal clamping and automatically-releasing device, so constructed that the target is securely held in place while the sending-arm is being swung around, and arranged in such manner as to automatically release the target 40 when in proper position for being thrown, and at the same time, by means of a pin or other stop, to give the target more axial rotation than it otherwise would receive by reason of centrifugal force alone. These features 45 and the advantages of my invention will more fully appear by reference to the accompanying drawings, which form a part of this specification, and in which similar letters of reference indicate like parts.

In said drawings I have shown at Figures 1 and 2 perspective views of a trap embodying 50 the best form of my invention. Figs. 3 and 4 are enlarged plan views of the same device, and Fig. 5 is an enlarged vertical sectional view of parts hereinafter described.

In the drawings, A represents the throwing 55 or sending arm of a trap, suitably pivoted at b on a standard, B, which arm is operated by a cord, C. The target A' is provided with lugs, projections, or recesses a', which engage with proper pins or projections, d and e, on the 60 clamping-arms D E. The arm D is pivoted to the swinging arm A at d', and I secure or pivot the arm E to said arm D at e'. The end of the arm A is provided with a cam, a, which operates on the pin or roller e' on the 65 end of the arm E. The flange d' and rubber ring or washer d' serve to secure the target more firmly when clasped by the arms D and E.

The operation of my invention is as follows: I first place the clamping-arm on one side of 70 the arm A, so that the pin or roller e will rest against the cam a at a point nearest the center or pivot d', as shown in Fig. 3, and then, placing one of the lugs against the pin e, I secure the edge or rim of the target under 75 the flange d', pressing it against the washer d' as I hook the pin e on the other lug of the target. The trap is now set and ready for use, as shown in Fig. 1. The cord C is now pulled and the arm A caused to swing around 80 on b as a center into the position shown in Figs. 2 and 4. As the arm E comes around, the cam a causes the pin or roller e' to operate, and on e' as a pivot the arm E is thrown out, and thus releases one of the lugs on the 85 target A', and as the target starts on its flight the pin d, holding the target back, as it were, by means of the disengaged lug, gives to the target a positive axial rotation. The target will thus be given an even and steady 90 flight of sixty-five to seventy-five yards.

I have shown what I deem to be the best method of reducing my invention to practice, but do not wish to be limited to the exact construction shown in the drawings, as modifications thereof will readily suggest themselves 95

to those skilled in the line of improvements to which my invention relates, which may be used with very good results and without departing from the principle thereof. 5. My invention is very simple, durable, and effective, requires no nice adjustment, has no weak parts to break or complicated parts to get out of order, and is quite cheap to manufacture.

What I claim, and desire to secure by Letters Patent, is—

1. In a trap for throwing targets, the target-clamping device herein shown and described, pivoted at or near the end of the throwing-arm of a trap, in combination with a double or two faced cam formed on the end of said arm, and a depending projection or pin on the clamping device, which bears against the cam during the swing of the 20 clamping device, releasing the same by its escape from the cam, and thereby allowing the target to escape, substantially as set forth.

2. In a trap for throwing targets, the clamping device shown, consisting of the arm D, pivoted near the end of the throwing-arm of the trap, 25 having pin d on one end, and the arm E, provided with pin e and roller e², pivoted at e' to the arm D, substantially as specified.

3. In a trap for sending targets, the clamping device consisting of the arm D, pivotally secured at or near the end of the throwing-arm of the trap, provided at one end with the engaging pin d, and at the other end with the pivoted arm E, having a target-engaging pin, e, in combination with the frictional washer 35 d², secured by the pin or pivot d' to the arm A, whereby, with the pins d and e, the targets are held in place, substantially as specified.

CHARLES F. STOCK.
